Charles E. Hinney
ATTORNEY.

UNITED STATES PATENT OFFICE.

JOSEPH P. GLASER, OF DETROIT, MICHIGAN, ASSIGNEE TO CHAMBERLIN METAL WEATHER STRIP COMPANY, OF DETROIT, MICHIGAN, A CORPORATION OF MICHIGAN.

VENTILATOR.

Application filed December 11, 1926. Serial No. 154,061.

This invention relates to ventilators and the object of the invention is to provide a ventilator which will shut out light but which will allow air to pass readily therethrough.

5 Another object of the invention is to provide a ventilator of the character described which may be opened or closed without admitting light.

10 A further object of the invention is to provide a ventilator through which sound will not readily pass and through which the occupants of a room cannot be seen.

15 These objects and the several novel features of the invention are hereinafter more fully described and claimed and the preferred form of construction by which these objects are attained is shown in the accompanying drawings in which—

20 Fig. 1 is an elevation of a door with one of the panels replaced with my improved ventilator.

Fig. 2 illustrates the ventilator as used in place of a transom.

25 Fig. 3 is an enlarged elevation of a portion of the ventilator at one end.

Fig. 4 is a section taken on line 4—4 of Fig. 3.

Fig. 5 is a section taken on line 5—5 of Fig. 3.

30 As shown in Figs. 1 and 2 a perforated metal plate 1 is provided which is movable horizontally in either direction to open or close the ventilator. As shown in Fig. 4 a space 2 is provided in which this plate 1 is movable

35 for opening or closing the ventilator. A series of plates 3 are provided as shown in Fig. 4 which are each formed to provide a parallel offset portion 4, the plates each having an angular portion 5 between the portions 3 and 4.

40 These plates are secured together in assembled relation in the frame 8 so as to provide spaces 6 and 7 between the plates on opposite sides.

45 The frame 8 with the plates secured therein in assembled relation is secured in the panel of a door or in place of a transom as shown in Figs. 1 and 2. In order to prevent the plates from binding so that the plate 1 cannot be moved the frame member 8 is slightly 50 wider than the stationary and movable plates therein as will be understood from Fig. 5. As will be understood from Fig. 3 when the plate 1 is moved to the right the perforations 9 therein are moved from the position shown in

full lines in Fig. 3 to that shown in dotted lines. As will be understood from Fig. 4 this movement of the plate 1 moves the apertures 9 behind the offset portions 4 of the plates 3 so that the ventilator is closed and no air can pass therethrough. When the ventilator is in 60 the open position shown in Fig. 4 air can pass through the apertures 7 and between the plate portions 3 and 4 and through the openings 6 and 9 into the interior of the room. This arrangement prevents direct drafts from 65 entering the room and at the same time prevents light from passing through the ventilator. This is a particularly valuable feature for ventilating hotel rooms in which the hall lights are left burning all night as this ventilator prevents any light from entering the room through the ventilator. Also due to the circuitous path which the air must take in 70 passing between the plates of the ventilator sounds will not readily pass through the ventilator. With this arrangement the occupant of the room cannot be seen and at the same time the room will be properly ventilated. 75 If desired a knob 10 may be secured to the center of the plate 1 by means of which the said plate may be readily moved to the opened or closed position.

By utilizing this ventilator in place of a transom a considerable saving is effected as no glass is needed and the usual hardware 80 for hinging and opening the transom is eliminated.

85 From the foregoing description it becomes evident that the device is very simple and efficient in operation, will not easily get out of order, is composed of sheet metal parts and is of consequent low manufacturing cost and provides a device which accomplishes the objects described.

90 Having thus fully described my invention, its utility and mode of operation, what I claim and desire to secure by Letters Patent of the United States is—

95 1. A ventilator comprising a frame member practically L shaped in cross section and substantially rectangular in form, a second frame member rabbeted in one face at the inner edge to receive the first frame, means for holding the L shaped frame in the rabbet, the assembled frames providing a channel in the inner periphery, a series of metal plates each offset in substantially its central portion providing parallel spaced portions of 100

substantially equal length, the series of plates being supported in the frame channel and so relatively arranged as to provide spaces between the plates, the edge of one plate being spaced relative to the aligned portion of an adjacent plate providing openings to the said spaces on opposite sides of the assembled plates, a third plate supported in the said frame channel on one side of the assembled plates and having apertures registerable with the said openings to said spaces, said third plate being slidable in the channel in face contact with the plate surfaces to bring the apertures into or out of registration with the said openings whereby the same may be opened or closed.

2. A ventilator comprising a frame member L shaped in cross section and substantially rectangular in form, a second frame member having a rabbet formed in one face adjacent the inner edge in which the first frame may be positioned, means for securing the first frame therein, the assembled frames providing a channel in the inner periphery defining the

frame opening, a series of metal plates supported at opposite ends in the oppositely disposed channel portions each formed with an offset portion extending in parallel relation with the body of the plate, the series of plates being so relatively arranged as to provide spaces between successive plates, the edge of one plate being spaced relative to the aligned portion of an adjacent plate providing openings to the said spaces on opposite sides of the assembled plates, a third plate having a width equal to the length of the said series of plates supported in the channel in contact with one face of the assembled plates and being less in length than the length between the bottoms of the channels of side portions of the assembled frames permitting movement of the third plate longitudinally in the channel, said third plate having apertures brought into or out of registration with the channel openings to open or close the same.

In testimony whereof I sign this specification.

JOSEPH P. GLASER.
